ENVELOPE PACKET

Alfred J. Hopkins, River Forest, Ill., assignor to
Gaw-O'Hara Envelope Company, Chicago, Ill.,
a corporation of Illinois

Application July 30, 1932, Serial No. 626,550

9 Claims. (Cl. 129—16)

This invention pertains to a device comprising a plurality of visibly indexed individually removable containers of the character of envelopes, all arranged normally in a convenient packet.

5 In general the object of this invention is to provide a device of this character so constructed as to make the device convenient to use and inexpensive to manufacture.

10 Various specific objects and advantages of this invention will be alluded to hereinafter or will become obvious from a perusal of this specification.

15 One preferred embodiment of the invention, selected for illustrative purposes is shown in the drawing.

Fig. 1 is a front elevation of the assembled device,

Fig. 2 is a central vertical section thereof,

20 Fig. 3 is a top view looking down upon the device of Fig. 1, and

Fig. 4 is a perspective view of one of the individual envelopes removed from the packet.

25 The illustrated embodiment of the invention is preferably constructed as follows.

20 A single sheet of paper is cut and folded as shown to provide a front face 11 and two overlapping rear sections 12 and 13 which are secured together in overlapped relation by adhesive 25 suitably supplied to form an outer envelope or pocket. The section 12 is provided with an upwardly extending tab 14 having a hole 15 with suitable reinforcing washers 16.

30 The lower portion of the sheet forming the front face is extended in the form of a flap 17 and folded up onto the back of the rear side of the pocket, being secured thereto by any suitable adhesive. The upper portion of the front face of the pocket is recessed as shown, providing the two downwardly sloping edges 18 and 19 and the bottom edge of the recess 20. This recess affords visibility to the upper margins of the several envelopes which are normally disposed in the 35 pocket.

35 A plurality of envelopes preferably of the character shown in Fig. 4 are provided. Each envelope generally indicated as 21 is preferably constructed to be opened along one of its long sides, hence when the packet is hung up on a wall by 40 means of any suitable hook passing through the opening 15, the opening of each envelope is arranged on one of its vertical sides. A simple flap free from mucilage and intended to be merely folded to close the envelope but not to be stuffed 45 therein is provided as in Fig. 4.

45 As clearly appears in Figs. 1 and 2, the shortest

5 of the envelopes, for example the one numbered 8, is placed at the front of the packet, the next shortest number 7 immediately thereafter, etc. Each of the envelopes when arranged in this fashion has enough of its upper margin visible so that numerals or words may be written thereon to indicate both the order in which the envelopes are to be filed and also what the contents are.

10 According to the present illustration, the packet is marked as it would be when employed for containing recipes, for example recipes clipped from newspapers and magazines. The user is compelled to remove each envelope from the packet before examining the recipes therein or before inserting or withdrawing any, consequently during this examination of the contents of a single individual envelope, no strain is placed upon the entire packet. Hence the pocket and the individual envelopes can be made of lighter and less tough material than would be required 15 if printed matter could be inserted into or withdrawn from the envelopes without removing them from the pocket. It will be noted that the individual envelopes are not as wide as the pocket, hence when they become stuffed with recipes 20 and cause distention of the outside envelope or pocket, they will still fit not too snugly in the pocket.

25 It is, of course, apparent that this packet of envelopes can be used for other than the collecting of recipes. The envelopes, for example, may be employed to contain bills for fuel, for light, for groceries, insurance and other such items, the nature of the contents of each envelope being conveniently written on that portion 30 of its margin which extends above the envelope immediately in front of it.

35 While the device, in the illustrated embodiment, is particularly suited for being hung on a wall, it of course may also be used without being hung up at all.

40 It should be further understood that the present disclosure reveals only a preferred embodiment selected for the purpose of illustrating the invention and that this invention is susceptible 45 of considerable modification without departing from the spirit and scope of the appended claims.

Having shown and described the invention, I claim:

50 1. An envelope packet comprising a plurality of superposed envelopes of progressively increasing length from the foremost to the rearmost, and a holder therefor constructed to removably hold said envelopes in such manner that the upper margin of each envelope is visible to an 55

extent sufficient to carry indexing information on such margins, each of said envelopes having three of its margins including said visible margin sealed and being provided with an opening along an edge which is perpendicular to its index margin, a marginal wall portion of said holder enclosing said openings and preventing access thereto unless the individual envelopes are withdrawn therefrom.

10 2. An envelope packet comprising a plurality of superposed envelopes of progressively increasing length from the foremost to the rearmost, and a holder therefor constructed to removably hold said envelopes in such manner that the
15 upper margin of each envelope is visible to an extent sufficient to carry indexing information on such margins, each of said envelopes being provided with an opening along an edge which is perpendicular to its index margin, each envelope having a flap folded over said opening, said holder and flap cooperating to prevent access to said openings unless the individual envelopes are withdrawn from the holder.

3. An envelope packet comprising a plurality of superposed envelopes of progressively increasing length from the foremost to the rearmost, and an expansible holder therefor constructed to removably hold said envelopes in such manner that the upper margin of each envelope is visible to an extent sufficient to carry indexing information on such margins, each of said envelopes having three of its margins including said visible margin sealed and being provided with an opening along a vertical edge thereof, at least the major portion of each said opening being concealed within said holder for preventing access to the interior of each envelope unless it is withdrawn from the packet.

4. An envelope packet comprising a plurality
40 of superposed envelopes of progressively increasing
length from the foremost to the rearmost,
and a holder therefor constructed to removably
hold said envelopes in such manner that the up-
per margin of each envelope is visible to an ex-
45 tent sufficient to carry indexing information on
such margins, each of said envelopes being pro-
vided with an opening along an edge thereof and
a flap folded over said opening, at least the major
portion of each of said openings and flaps being
50 concealed within said holder for preventing ac-
cess to said openings unless the individual enve-
lopes are withdrawn from the holder.

5. An envelope packet comprising a plurality of superposed envelopes of progressively increasing length from the foremost to the rearmost, and an expansible holder therefor constructed to removably hold said envelopes in such manner that the upper margin of each envelope is visible to an extent sufficient to carry indexing information on such margins, each of said envelopes being provided with an opening along an edge thereof and with a flap folded over said

opening for closing the same, at least the major portion of each said flap being concealed within said holder for preventing access to said openings unless the individual envelopes are withdrawn from the holder, the front wall of said holder being recessed downwardly from the top, said recess being horizontally narrower than the horizontal width of said envelopes and of a depth sufficient to expose all of said indexed margins. 5

6. An envelope packet comprising a plurality of superposed envelopes of progressively increasing length from the foremost to the rearmost, and a holder therefor constructed to removably hold said envelopes in such manner that the upper margin of each envelope is visible to an extent sufficient to carry indexing information on such margins, each of said envelopes being provided with an opening and closure means therefor positioned on each envelope enclosed by a lateral marginal portion of the holder for preventing access to each envelope until it is withdrawn from the holder. 10 15 20

7. An envelope packet comprising a plurality of superposed envelopes of progressively increasing length from the foremost to the rearmost, and a resiliently expansible holder therefor constructed to removably hold said envelopes in such manner that the upper margin of each envelope is visible to an extent sufficient to carry indexing information on such margins, each envelope having an opening along an edge perpendicular to its index margin and being constructed and so located in the holder that the resilient walls of the holder enclose it and prevent access to the envelope unless withdrawn from the holder. 35

8. An envelope packet comprising a plurality of superposed envelopes of progressively increasing length from the foremost to the rearmost, and a resiliently expansible holder therefor constructed to removably hold said envelopes in such manner that the upper margin of each envelope is visible to an extent sufficient to carry indexing information on such margins, each envelope having an opening normally concealed within and held closed by the resilient walls of the holder for preventing access to the envelope unless it be withdrawn from the holder. 40 45

9. An envelope packet comprising a plurality of superposed envelopes of progressively increasing length from the foremost to the rearmost, and a resiliently expansible holder therefor constructed to removably hold said envelopes in such a manner that one sealed margin of each envelope is visible to an extent sufficient to carry indexing information on such margins, at least three margins of each envelope being sealed, each envelope having an opening normally concealed within and held closed by the resilient walls of the holder for preventing access to the envelope unless it be withdrawn from the holder. 60
